(57) CLAIM

We claim the ornamental design for a staple collation, as shown and described.

DESCRIPTION

FIG. 1 is a front perspective view of a staple collation in accordance with a first embodiment of the present invention. FIG. 2 is a front view of the staple collation of FIG. 1. FIG. 3 is a rear view of the staple collation of FIG. 1. FIG. 4 is a right-side view of the staple collation of FIG. 1. FIG. 5 is a left-side view of the staple collation of FIG. 1. FIG. 6 is a top view of the staple collation of FIG. 1. FIG. 7 is a bottom view of the staple collation of FIG. 1. FIG. 8 is a front perspective view of a staple collation in accordance with a second embodiment of the present invention.

FIG. 9 is a front view of the staple collation of FIG. 8.

FIG. 10 is a rear view of the staple collation of FIG. 8.

FIG. 11 is a right-side view of the staple collation of FIG. 8.

FIG. 12 is a left-side view of the staple collation of FIG. 8.

FIG. 13 is a top view of the staple collation of FIG. 8.

FIG. 14 is a bottom view of the staple collation of FIG. 8.

FIG. 15 is a front perspective view of a staple collation in accordance with a third embodiment of the present invention.

FIG. 16 is a front view of the staple collation of FIG. 15.

FIG. 17 is a rear view of the staple collation of FIG. 15.

FIG. 18 is a right-side view of the staple collation of FIG. 15.

FIG. 19 is a left-side view of the staple collation of FIG. 15.

FIG. 20 is a top view of the staple collation of FIG. 15.

FIG. 21 is a bottom view of the staple collation of FIG. 15.

FIG. 22 is a front perspective view of a staple collation in accordance with a fourth embodiment of the present invention.

FIG. 23 is a front view of the staple collation of FIG. 22.

FIG. 24 is a rear view of the staple collation of FIG. 22.

FIG. 25 is a right-side view of the staple collation of FIG. 22.

FIG. 26 is a left-side view of the staple collation of FIG. 22.

FIG. 27 is a top view of the staple collation of FIG. 22.

FIG. 28 is a bottom view of the staple collation of FIG. 22.

FIG. 29 is a front perspective view of a staple collation in accordance with a fifth embodiment of the present invention.

FIG. 30 is a front view of the staple collation of FIG. 29.

FIG. 31 is a rear view of the staple collation of FIG. 29.

FIG. 32 is a right-side view of the staple collation of FIG. 29.

FIG. 33 is a left-side view of the staple collation of FIG. 29.

FIG. 34 is a top view of the staple collation of FIG. 29.

FIG. 35 is a bottom view of the staple collation of FIG. 29.

FIG. 36 is a front perspective view of a staple collation in accordance with a sixth embodiment of the present invention.

FIG. 37 is a front view of the staple collation of FIG. 36.

FIG. 38 is a rear view of the staple collation of FIG. 36.

FIG. 39 is a right-side view of the staple collation of FIG. 36.

FIG. 40 is a left-side view of the staple collation of FIG. 36.

FIG. 41 is a top view of the staple collation of FIG. 36; and,

FIG. 42 is a bottom view of the staple collation of FIG. 36.

The broken lines in the drawings illustrate portions of the staple collation and form no part of the claimed design. The dot-dash-dot broken lines in the drawings define the bounds of the claim and form no part thereof.
